UNITED STATES PATENT OFFICE

2,674,054

SPRINKLING FLATIRON

Henry Maykemper, Eau Claire, Wis., assignor to
National Presto Industries, Inc., a corporation
of Wisconsin

Application May 3, 1950, Serial No. 159,783

15 Claims. (Cl. 38—78)

1 My invention relates to a flat iron—sometimes known as a pressing iron—and more particularly to a flat iron having a built-in spraying or sprinkling device.

2 My invention may be readily incorporated in a flat iron which is electrically heated by a coil carried within the sole plate, or which is heated by other means associated with the iron, or by heating means entirely separate from the iron. While my invention is shown incorporated with a flat iron having a heating coil in the sole plate, that is for purposes of illustration and not by way of limitation.

3 It is well known that dampening of material to be pressed makes the pressing operation easier and causes the material to retain its pressed condition longer. For many decades it has been the practice, before ironing clothes, to sprinkle them by using a bottle having a spray head, or by a similar device. Such sprinkling may not be uniform. To overcome the lack of uniformity of sprinkling, some persons follow the practice of rolling up the clothing which has been sprinkled so that the moisture will spread. Sometimes, the sprinkling operation is carried on some hours before ironing and even the night before the ironing is to be done.

4 While flat irons have been developed which provide their own steam which discharges from the iron, there are some persons who do not like to use such an iron and there are also certain limitations in such an iron, for example, limitations as to the amount of moisture which such an iron can continue to discharge before requiring refilling.

5 It is one of the advantages of my invention that I can provide a flat iron of no more than ordinary size which incorporates a reservoir carrying sufficient water, or other moistening agent, to adequately dampen a weekly wash for a family of four without requiring refilling. By my invention, the release of water, or the like, is under the complete control of the user at all times and, consequently, none of the water is wasted.

6 Tests seem to indicate that the application of a wetting agent, such as water, immediately before ironing, is more effective than the usual sprinkling operation wherein the clothes are allowed to sit for some time after being sprinkled. It also appears that a fine mist of water or other wetting agent is superior to large drops of water, such as are used in the usual sprinkling operation. A fine mist of water has a further advantage of covering a larger surface of material with a single spraying application than is possible

7 with the same amount of water sprinkled on the clothing. It is possible to use various wetting agents, and the addition of chemicals and dyes to the wetting agent will permit many operations not heretofore possible or convenient. A small amount of borax, for example, may be added to the wetting agent, such as water, and when sprayed on the material prior to ironing results in a new look to the material after the ironing operation is completed.

8 It is one of the objects of my invention to dispose the fluid reservoir within the usual housing or body or shell of a flat iron. The housing may itself form one of the walls of the reservoir. The reservoir is thereby concealed from view, so that the iron may present a more pleasing appearance.

9 It is another object of the invention to provide easy means of access to the reservoir, for filling the same, by the use of structure which is easily and inexpensively assembled and which will not detract from the attractive appearance of the iron.

10 While it is entirely satisfactory to have the fluid in the reservoir warm, it is not desired to have it highly heated, and I therefore provide means for preventing the heat from the sole plate from heating the fluid in the reservoir to an undesired degree. Preferably, the reservoir is spaced from the sole plate and any contact of the housing with the sole plate is at spaced apart locations and consists substantially of point contacts. Such spacing and limited areas of contact permits the space between the sole plate and reservoir and housing to form an air passageway so that air may circulate therethrough as the iron is moved backwardly and forwardly in the ironing operation. In that manner, the heat given off upwardly toward the reservoir and housing by the sole plate is dissipated to a substantial extent.

11 Also, the fastening means employed for securing the handle, housing and sole plate together are of such a construction that a minimum transference of heat is provided.

12 It is a further object of the invention to provide a novel arrangement of spray mechanism and actuating mechanism therefor in the body or handle, or in both together in some forms of the invention.

13 It is yet another object of the invention to provide a convenient form of pump mechanism for discharging a fluid spray from the reservoir to the material to be dampened.

14 It is a further object to provide in the forward portion of the handle of the iron a generally

vertical bore in which a filler tube for the reservoir may be disposed.

It is yet another object of the invention to provide for pump mechanism which may be removable through the filler tube mentioned above.

It is another object of this invention to provide a filler tube for the reservoir which also serves as a portion of the pump mechanism.

Other objects, uses and advantages of the invention will become apparent, or be obvious, from a consideration of the following description and the drawings, in which:

Figure 1 is a side view, partially in section, showing one embodiment of my invention;

Figure 2 is a fragmentary view, partly in section and partly in elevation, of a second embodiment of my invention;

Figure 3 is a side view, partially in section, of another modification of the invention;

Figure 4 is a side view, partially in section, of yet another modification of my invention; and

Figure 5 is a sectional view of valve means suitable for use in the apparatus of my invention.

To the extent practicable, the same reference numerals have been employed in the different figures of the drawings to indicate the same or substantially similar structures.

Referring first to Figure 1, I have shown an iron comprising the usual form of sole plate 1 which is adapted to have a known form of wired heating unit 2 associated therewith. A body or housing or shell, indicated by the reference numeral 3, is disposed above the sole plate in a customary manner and is connected with the sole plate by fastening means, such as the hollow threaded fastening element 4 and the hollow threaded fastening element 5. Element 4 has a head which bears against the bottom wall, or plate, 7 of the water reservoir 6, and its lower threaded end is threaded into a socket in the sole plate 1. The headed fastening element 5 has its head resting against a portion of the handle 8 and extends through the uppermost wall of the housing 3, at its rear portion, and is threaded into a socket in the sole plate 1. If desired, insulating material may be placed in the hollow fastening means 4 and 5.

While the upper portion of the housing 3 forms a portion of the reservoir, it will be understood that a separate tank structure could be disposed beneath the upper surface of the housing, or shell, 3. The reservoir 6 is adapted to be filled with water or some other appropriate wetting agent, and the filling is accomplished through the filler tube 9, which extends vertically upwardly from the reservoir 6 to a position adjacent the top of the handle 8. Fluid introduced into the filler tube 9, upon removal of the stopper 10, gains entrance to the reservoir 6 through the passageways 9a in the head of the fastening element 4, which passageways extend through the side wall of the tube 9 and communicate with the reservoir 6. If preferred, openings in the side wall of the tube 9 adjacent its lower end may be employed.

The forward portion of the handle 8 has a generally vertical bore, as shown, through which the filler tube 9 extends upwardly. Where the filler tube extends upwardly through the top wall of the housing 3, a water-tight joint is formed in a known manner, and the filler tube 9 is secured by its lower end to the bottom wall 7 of the reservoir about the headed fastening element 4.

The heating element 2 is connected in series

with a thermostatic control 13, which is manipulated from outside of the iron through the control knob 15 and its shaft 14, all in a known manner. From the thermostatic control 13, there is electrical connection to the wires 12 and outwardly through the handle to a standard form of electric cord, which is adapted to be plugged into a wall socket, or the like.

A spacing washer 18 of insulating material surrounds the fastening element 4 and is interposed between the under surface of bottom wall 7 of the reservoir and the top surface of the sole plate 1. At the rear of the iron, the fastening element 5 may have a sleeve 5a surrounding it and formed of insulating material to assist in minimizing the transfer of heat from the sole plate to the housing 3. The sole plate 1 is provided with rest points 16 which may have ball point insulators 17, of ceramic or other heat resistance material, which will serve to space the flange of the housing 3 from the sole plate, in conjunction with the spacing washer 18. While it is not objectionable to have the fluid in the reservoir warm, it is not desired that it be boiling or at other high temperatures which would be dangerous to the user of the iron, and therefore the iron is formed to minimize the transfer of heat upwardly from the sole plate to the reservoir and the walls which define it. It has been found that by providing an air space as an insulating medium that the temperature of the water may be maintained at a desired level, since, in the ironing operation, with the iron being moved backwardly and forwardly, the space between the sole plate and reservoir forms an air passageway through which air flows and dissipates the heat which might otherwise undesirably heat the water in the reservoir.

The means providing a fluid outlet consists of a tube 22 extending through an aperture in the resilient stopper 10 of the filler tube 9, said tube 22 extending downwardly through the filler tube to a position adjacent its lower end and just above the bottom wall 7. The tube 22 also extends into a cap 25, which is connected with the stopper 10, and a ball spray nozzle 26 communicates with the tube 22 and provides for discharge in a forward direction from the iron. The spray nozzle 26 is adjustable in direction and also permits variation, by manual adjustment in a known manner, in the amount and density of the spray. The spray nozzle 26 and its supporting structure is carried by the cap 25, and, by gripping the cap between the fingers, it and the stopper 10 tube 22 and spray nozzle 26 may be withdrawn together from the filler tube 9 so that additional fluid may be poured into the filler tube to fill the reservoir 6.

The means for causing discharge of fluid through the fluid outlet means, such as tube 22 and nozzle 26, comprises, in Figure 1, a rubber, or resilient plastic, bulb 27 of a known type, which is disposed in a recess 27a in the underside of the handle 8, as clearly shown. A portion of the bulb 27 extends below the handle, whereby it may be easily gripped and squeezed by the fingers. The bulb 27 is held in place at its rear by a screw 28, said screw and the rear end of the bulb seating in a socket in the tail insert, or plate, 8a of the handle 8. At its forward end, the bulb 27 has a passageway 27b which provides communication between the interior of the bulb 27 and a known form of double valve structure, indicated generally by the reference numeral 30. The air-valve structure 30 is connected with a

tube 29 which leads to reservoir 6. The valve structure 30 permits air intake, as the bulb expands, while shutting off communication with the tube 29, which leads to the reservoir 6. When the bulb is filled with air and is then compressed by the fingers, the valve structure 30 closes off passage of air to the outside of the handle and opens up to pass air through the passageway 29 to the reservoir, whereupon water is forced through the passageways 9a and into the filler tube 9 and up the tube 22 and out the spray nozzle 26.

In the modification shown in Figure 2, the structure of the iron, generally, is the same as that shown in Figure 1, including the sole plate 1, heating element 2, housing 3, fastener 4 threaded to the sole plate and having ports 9a therein, reservoir 6 having bottom 7, handle 8, point contacts 16, 17, and insulator 18, but the means for causing discharge of fluid from the reservoir through a spray nozzle is different from that shown in Figure 1. In particular, a relatively short filler tube 40 is secured to the top wall of the housing 3 and extends upwardly therefrom, the tube 40 being closed at its upper end by a removable stopper 41. The stopper 41 includes an axial bushing 42 in which a tube 43 is adapted to reciprocate and serve as a piston rod. The tube 43 at its lower end passes into a pump cylinder 44 and is connected with, and has communication through, a piston 45. The piston reciprocates in the pump cylinder 44, which cylinder is provided with a perforate bottom wall rested on the head of the fastener 4. A spring 46 normally urges the piston and tube 43 upwardly. In the showing of Figure 2, the piston is in its lowermost position, with the spring compressed.

Tube 43 extends through the bushing 42 in stopper 41 and is connected with the cap 47 and communicates with a spray nozzle 48, which is carried by said cap. The nozzle may be adjusted in direction. The cap 47 normally will be in a position above that shown in Figure 2, due to the urging of spring 46 in the pump cylinder 44. The cap 47 is located at the forward end of the handle 8, and may conveniently be depressed by the thumb or finger of the person using the iron. In this embodiment of the invention, the ports 9a are controlled by inwardly opening or inlet valves, that is, valves that are opened upon the creation of a vacuum pressure condition within the cylinder 44 to accommodate in-flow of water and that are closed on the pressure stroke of the piston 45 to accommodate discharge of water through the tube 43. In some instances, it will be desirable to provide a valve in the tube 43 to prevent entry of air on the suction stroke of the piston. When the cap 47 is depressed, the tube 43 and its piston 45 descend in the pump cylinder 44 and the fluid in said cylinder is then forced upwardly through tube 43 and out of the spray nozzle 48. The valved passageways 9a in the bottom of the pump cylinder 44 and in the head of the threaded fastening element 4 provide communication with the water or other liquid in the reservoir 6. If preferred, passageways may be formed in the side walls of the pump cylinder 44 adjacent its lower end.

When it is desired to fill the reservoir 6, it is only necessary to raise the cap 47 and the stopper 41, whereupon the cap 47, nozzle 48, stopper 41 and pump cylinder 44 may be removed through the filler tube 40 and then replaced when the reservoir has been filled.

In the modification shown in Figure 3, the 75 surface of piston 83, and normally urges the pis-

iron as a whole is quite similar to that shown in Figure 1. In particular, the iron includes a sole plate 1, heating element 2, housing 3, fastener 5, sleeve 5a, reservoir 6 having bottom wall 7, handle 8 and handle insert 8a, electrical conductor 12, thermostat 13, thermostat control shaft 14 and knob 15, point contacts 16 and spacer 18. In this embodiment of this invention, a filler tube 61 is secured to the top and bottom walls of the reservoir and extends vertically through the reservoir and upwardly therefrom. At its lower end, which extends through the wall 7 of the reservoir, the filler tube is closed by a bottom plate 61a threaded therein, which plate is secured to the sole plate, on top of the insulator 18, by a fastener or screw 62. In this manner, the filler tube 61 also serves as a pump housing or cylinder. Adjacent the lower end of tube 61, there is a valved inlet opening 63 communicating with the reservoir 6 and a valved outlet opening 64 communicating between the tube 61 and a duct or passageway 65 which comprises the fluid outlet means in this form of the device. Duct 65 at its upper end communicates with a spray nozzle 66, which, as in the other forms of the invention, is adjustable as to direction and density of spray.

A spring 67 acts between the bottom plate 61a and the underside of a piston 68, and normally urges the piston 68 and its connecting rod 69 upwardly from the lowermost position in which the piston is shown in Figure 3. The piston rod 69 has a fast-feed thread 70 at its upper end, by means of which it is connected to a threaded socket in a cap 71. Cap 71 has an annular groove 72 adjacent its periphery and opening on its underside, which groove is adapted to fit over the upper end of the wall of tube 61 to form a closure therefor. The cap 71 may be pressed downwardly against spring 67 by the thumb or finger of the user of the iron, and the cap has sliding bearing support on the upper end of the filler tube 61.

A slight rotation, such as a quarter turn, of the cap 71 with respect to the piston rod 69 will disengage the cap so that it may be removed and water, or other wetting agent, may be poured into the filler tube 61. The water poured into the tube flows into the reservoir 6 through the series of openings 73 in the wall of tube 61, above the uppermost position of the piston 68, which uppermost position is indicated in dotted lines in Figure 3.

Referring now to Figure 4, another modification of the invention is illustrated. The structure of the iron itself is much the same as previously described and includes a sole plate 1, heating element 2, housing 3, fastener 5, reservoir 6 having bottom wall 7, handle 8 and handle insert 8a, cord 12, thermostat control shaft 14 and knob 15, point contacts 16 and insulator 18. In this form of the iron, however, the vertical bore at the forward end of the handle 8 includes not only a filler tube 80 extending vertically upward from the bottom 7 of the reservoir 6 and having a threaded closure cap 81 adjacent the top forward portion of handle 8, but there is also included in the bore a pump cylinder 82 which is separate from the filler tube 80. The valved piston 83, of a known type, is reciprocable within the pump cylinder 82 by a piston rod 84, which has a knob 85 at its upper end. The rod 84 is guided in a bearing in the top enclosure, or head, 86 of the pump cylinder 82. A spring 87 acts between the head 86 and the top 75 surface of piston 83, and normally urges the pis-

ton and rod 84 downwardly to the position shown in Figure 4. The top of the knob 85 of the piston rod 84 and the top of threaded cap 81 for the filler tube 80 both lie in a plane beneath the spring snap lid 88, which is hingedly connected at the top of the handle 8.

A fluid outlet means for the fluid in reservoir 6 comprises the conduit 89 which leads directly from a location adjacent the bottom of reservoir 6 to the nozzle 90, at the forward end of the iron. A valve 91 is interposed in the fluid outlet means leading to the nozzle 90 so that air pressure may be built up and maintained within the reservoir 6 by the air pump structure. Valve 91 is under the control of a spring loaded push button 92, which is connected to a connecting rod 93 of the valve 91. The valve 91 is normally closed and its push button is conveniently located adjacent the top surface of the forward portion of the iron.

Preparatory to using the form of the iron illustrated in Figure 4, the hinged lid 88 is raised and screw cap 81 of the filler tube 80 is removed. Water is then added to the reservoir and the cap 81 is then replaced. Next the pump is actuated by raising and lowering the piston 83 by means of the knob 85 to pump air into the reservoir. To this end, the piston 83 includes a valve opening in the direction of the lower side of the piston for controlling the flow of air to the opposite sides of the piston, and outlets 94 and 95, disposed adjacent the lower end of the pump cylinder 82, are provided with outwardly opening valves so that as the piston is reciprocated air is introduced, through ports in the closure 86, the valve port in the piston 83 and the valve outlets 94 and 95, to the interior of the reservoir 6 so that an internal pressure of several pounds in excess of atmosphere may be provided. Then, with the piston in its lower position, it is only necessary to press the push button 92 when it is desired to spray fluid through the nozzle 90, since the pressure existing in the reservoir urges the fluid outwardly through the fluid outlet means, or conduit, 89 past valve 91 and out of nozzle 90.

In Figure 5, I have shown a valve suitable for use in the various embodiments of my invention disclosed herein. The valve comprises a hollow body 50 having a bore therein adapted to be closed by a threaded plug 51. The body 50 and the plug 51 define an inlet port 52, an outlet port 53 and valve seats 54 and 55, respectively, adjacent each port. Mounted within the body 50 is a valve 56 having a head 57 adapted for co-operation with either one of the seats 54 and 55. A spring 58 biases the valve 56 into normal engagement with its seat. The valve is adapted to be mounted with the body 50 thereof disposed to the inside of and connected, by means of a clip 59, to a wall member 60. In the embodiment of the invention shown in Figure 4, the wall member 60 suitably comprises the peripheral wall of the cylinder 82 with a valve member being disposed in each of the ports 94 and 95. In this embodiment, the valves mounted in the ports 94 and 95 are required to be outlet valves and, accordingly, the valve 56 is so disposed that the head 57 thereof cooperates with the seat 55 for the port 53 in the plug 51 of the valve. Thus, as air is compressed beneath the piston 83, the valve 56 will be forced open to accommodate flow of air through the body of the valve and into the reservoir 6. Also, the piston 83 is provided with a valve and in this use, the wall 75

member 60 may suitably comprise the end face of the piston 83 with the valve projecting downwardly from the lower face of the piston. In this use, the valve is required to be an inlet valve for controlling the flow of air through the piston 83 and, accordingly, the valve would be used as the same is shown in Figure 5. In the embodiment of the invention shown in Figure 3, the valve disposed within the port 63 is required to be an inlet valve and the valve disposed in the port 64 is required to be an outlet valve. Accordingly, two valve members corresponding to the valve 50 must be mounted to the interior of the cylinder 61. The valve associated with the port 63 will have the arrangement shown in Figure 5 wherein the head 57 of the valve 56 cooperates with the seat 54 of the inlet port 52. The valve mounted within the outlet port 64 is required to be an outlet valve and, accordingly, the valve 56 will be disposed with the head 57 thereof in normal engagement with the seat 55 controlling the outlet port 53. In the embodiment of the invention shown in Figure 2, the arrangement of the valves is required to be the opposite of the arrangement provided in the embodiment of the invention shown in Figure 4. Specifically, the valves disposed within the ports 9a are required to be inlet valves and the valve disposed within the tube 43 is required to be an outlet valve, as will be obvious.

With respect to the modifications of the invention shown in Figures 1, 3 and 4, the fastening means, spacing means, and insulated point contacts between the housing and sole plate, are substantially the same as shown in Figure 1 and provide a similar insulating arrangement to prevent undue transfer of heat to the reservoir and handle. In addition, to the extent that heat is taken on by the water in the reservoir, it serves to reduce the amount of heat which may reach the handle.

While I have illustrated preferred embodiments of my invention, I do not intend to be limited thereto, except insofar as the appended claims are so limited, since various changes and modifications, coming within the scope of the invention, will suggest themselves to others by reason of my disclosure.

I claim:

1. A flat iron comprising a sole plate, a housing disposed above and connected with said sole plate; spacers defining limited points of contact between said housing and said sole plate and spacing said housing from said sole plate whereby a passageway for air circulation is provided therebetween; a handle for manipulating the iron, said handle at its forward end having a vertical bore; fastening means for connecting the housing, handle and sole plate together; said housing including wall means defining a fluid reservoir within the housing; a filler tube extending into the bore in said handle and establishing communication between the top forward portion of said handle and said reservoir; a removable closure for said filler tube in the bore in said handle; conduit means defining a fluid outlet leading from said reservoir to a position adjacent the forward end of the iron; and manually operable pump means associated with said handle and under the control of the user for discharging fluid from the reservoir outwardly through the fluid outlet means.

2. The iron of claim 1 wherein the fastening means for connecting the housing, handle and sole plate together are hollow and provide lim-

ited areas of engagement between the sole plate and housing, whereby the sole plate and housing engage only at substantially point contacts.

3. The iron of claim 1 wherein the handle includes a horizontal portion having a recess in its under side and wherein the pump means comprises a flexible bulb partially disposed in said recess and partially extending out of said recess, said bulb having a valve controlled air inlet and a valve controlled air outlet, said air outlet communicating with said reservoir, whereby actuation of said bulb results in establishment of air pressure on the fluid in said reservoir to force the fluid through said outlet means.

4. The iron of claim 1, wherein the pump means includes a valved pump cylinder in the reservoir, a piston reciprocable in said cylinder, and a piston rod extending through said filler tube to adjacent the top of the handle for manually actuating said piston, said cylinder, piston rod and piston being disconnectable from the iron and removable through the upper end of the filler tube upon removal of said closure.

5. The iron of claim 1 wherein the fluid outlet means extends upwardly through the filler tube.

6. The iron of claim 5 together with an apertured stopper at the upper end of said tube, with the fluid outlet means extending through said aperture in the stopper.

7. The iron of claim 6 together with a pump cylinder in said reservoir and a piston reciprocable in said cylinder, and wherein the fluid outlet means has reciprocal movement through the aperture in said stopper and is connected at one end with the piston and communicates with the reservoir through said cylinder and said piston.

8. The iron of claim 1 wherein the filler tube communicates with the reservoir through openings in the side walls of the filler tube and wherein the tube extends to the bottom of the reservoir and is closed off at its lower end; together with a valve inlet adjacent the lower end of said tube, a valved outlet adjacent the lower end of said tube establishing communication between said tube and said fluid outlet means, and a reciprocable piston in said tube beneath the openings in its side walls for drawing fluid from the reservoir into the tube and for discharging fluid from the tube to the fluid outlet means.

9. The iron of claim 8 wherein the piston has a connecting rod which extends upwardly through the filler tube and has operative association with the closure for said filler tube.

10. The iron of claim 9 wherein the closure for said filler tube is located adjacent the top of the handle at the forward end thereof and is slidably associated with said filler tube, whereby it may be manipulated by a thumb or finger of the user of the iron to actuate the pump piston.

11. The iron of claim 1 wherein the fluid discharging means comprises an air pump communicating with the reservoir, and including a valved pump cylinder and reciprocable piston therein, said cylinder and piston extending upwardly through the bore in said handle to a position adjacent the top of the handle, said piston being adapted for manual actuation to force air into said reservoir to establish a pressure on the fluid in the reservoir tending to discharge the fluid, and a manually operable valve controlling the flow of fluid from the reservoir through the fluid outlet means.

12. The iron of claim 11 wherein a cover hinged to the top of the handle closes the bore in the handle at its upper end.

13. A flat iron comprising a sole plate, a housing disposed above and connected with said sole plate, spacers defining limited points of contact between said housing and said sole plate and spacing said housing from said sole plate whereby a passageway for air circulation is provided therebetween, a handle for manipulating the iron, said housing including wall means defining a fluid reservoir within the housing, fastening means for connecting the housing, handle and sole plate together and for defining a limited conductive path between said sole plate and said reservoir, said handle at its forward end having a vertical bore therethrough, a filler tube extending into the bore in said handle and establishing communication between the top forward portion of said handle and said reservoir, a removable closure for said filler tube in the bore in said handle, conduit means defining a fluid outlet leading from said reservoir to a position adjacent the forward end of the iron, said conduit means terminating in a nozzle directed forwardly of the iron, and manually operable pump means disposed in said reservoir and extending through the bore in said handle and terminating adjacent the top of the handle for manual actuation, said pump means being under the control of the user for discharging fluid from the reservoir outwardly through the fluid outlet means.

14. A flat iron as set forth in claim 13, wherein said nozzle is adjustably mounted adjacent the forward portion of said handle for varying the direction of spraying fluid from said reservoir.

15. A flat iron comprising a sole plate, a housing disposed above and connected with said sole plate, a handle disposed above and connected with said housing for manipulating the iron, said handle at its forward end including a vertical portion extending adjacent said housing, said handle having a vertical bore therethrough in the said vertical portion thereof, said housing having an aperture therein in alignment with the vertical bore in said handle, said housing including wall means defining a fluid reservoir within the housing, a filler tube disposed in the bore in said handle and extending through the aperture in said housing and extending into the bottom of the reservoir within the housing, said filler tube being sealingly secured to said housing around the aperture through said housing and at the bottom of said reservoir, a piston reciprocable in said filler tube, a spring between said piston and the bottom of said reservoir for normally biasing said piston away from the bottom of said reservoir, said filler tube having a plurality of radial openings therein above the normal spring biased position of said piston, said radial openings in said filler tube communicating with said reservoir, said filler tube adjacent the bottom of said reservoir having a radial inlet port and a radial outlet port therein, an inlet valve controlling the inlet port in said filler tube, an outlet valve controlling the outlet port in said filler tube, a fluid discharge tube disposed adjacent said filler tube and extending to the exterior of said housing, a spray nozzle adjustably associated with said discharge tube to the exterior of said housing, said nozzle being disposed forwardly of said handle and being directed to spray forwardly of said sole plate, said discharge tube communicating directly with the outlet port in said filler tube, said piston including a piston

11

rod extending upwardly through said filler tube, a closure for said filler tube associated with the upper end thereof and reciprocable with respect thereto within the bore in said handle, said piston rod being operatively associated with said closure for said filler tube, said closure being adapted to be reciprocated axially of said filler tube by the user of the iron to operate said piston, whereby said piston operating in said filler tube pumps fluid from said reservoir to said discharge tube and through said nozzle. 10
